DUSTPAN

John W. Smith, 5035 N. 51st St.,
Boulder, Colo. 80302

Filed Apr. 14, 1969, Ser. No. 16,707

Term of patent 14 years

Int. Cl. D7—06

U.S. Cl. D49—28

FIGURE 1 is a top plan view of a dustpan showing my new design, a portion of the overhanging top having been broken away and shown in section to reveal the stiffening webs;

FIGURE 2 is a bottom plan view thereof;

FIGURE 3 is a front elevation;

FIGURE 4 is a rear elevation;

FIGURE 5 is a right side elevation; and,

FIGURE 6 is a left side elevation.

I claim:

The ornamental design for the dustpan, as shown.
